UNITED STATES PATENT OFFICE.

HENRY F. KELLEMEN, OF UTICA, NEW YORK, ASSIGNOR TO UTICA DROP FORGE & TOOL COMPANY, OF UTICA, NEW YORK.

CUTTING-PLIERS.

No. 896,118.

Specification of Letters Patent.

Patented Aug. 18, 1908.

Application filed November 8, 1906. Serial No. 342,448.

To all whom it may concern:

Be it known that I, HENRY F. KELLEMEN, of Utica, in the county of Oneida and State of New York, have invented certain new and 5 useful Improvements in Compound Cutting-Pliers; and I do hereby declare that the following is a full, clear, and exact description thereof, which will enable others skilled in the art to which it appertains to make and 10 use the same, reference being had to the accompanying drawings, and to the letters of reference marked thereon, which form part of this specification.

The object of my present invention is to 15 provide an improved construction of compound cutting pliers, wherein provision is made for reducing to a minimum the cost of constructing the parts and the cost of assembling the same, and which pliers are strong 20 and efficient and capable of being conveniently taken apart to sharpen, repair or otherwise, and have an open throat, and side plates into and through which wire or other material to be cut can be inserted to any 25 length desired.

Figure 1 of the drawings shows a side elevation of my improved pliers, with the jaws and lever handle in open position. Fig. 2 shows the same with one of the side plates 30 removed and the bolts shown in section. Fig. 3 shows the same as Fig. 2, with parts in closed position. Fig. 4 is an edge view of the complete pliers. Fig. 5 shows a section on line A—B of Fig. 1. Fig. 6 is a longitudinal 35 section showing particularly how a wire may be passed through the throat and side plate.

Referring to the reference letters and figures in a more particular description, 2—2 indicates the cutting jaws, which include the 40 lever portions 2^a, which lever portions are preferably thinner and plate-like parts and beveled as to their contiguous edges. The rear ends of the lever parts 2^a are provided with sockets 2^b, which receive the ball joint 45 3^a of the lever handles 3. The pivoted ends 3^b of the lever handle 3 are of the same thickness as the lever parts 2^a of the jaws, and include sockets which receive the connecting roller 4 and provide stop shoulders 50 5 and 6 at either side of these sockets. The side plates 6 receive the jaw levers 2^a and pivoted ends of the lever handle 3 therebetween, and the plates are held together and

pivots provided for the jaws 2 by the bolts 7 and for the lever handle 3 by the bolts 8. 55 The center portions of the plates 6 are cut out as indicated at 9, whereby provision is made for inserting a wire or piece of material through the throat between the jaws and levers and out through said opening, as shown 60 in Fig. 6, and the operation of the working parts may be better observed, any chip or piece readily dislodged or expelled, and the position of the inner end of a piece of wire or material inserted down the throat of the 65 pliers may be observed. The beveled edges on the levers 2^a serve to direct a wire inserted through the throat out at the side through the opening 6.

It will be noted that the rear ends of the 70 plates 6 are of such shape and so positioned that they will confine the connecting roller 4 from lateral displacement, no matter whether the lever handles 3 are in open or closed position. Between the lever handles 3 there is 75 provided the spring 10 for throwing the levers and jaws into open position, the same being retained in sockets provided in the lever handles.

It will be noted that the jaws 2 with their 80 lever portions 2^a are duplicate parts; that the lever handles 3 are duplicate parts, and that the side plates 6 are duplicate parts, and the four bolts employed are also duplicates, and these parts constitute substantially the 85 whole of the pliers. This, among other things, enables me to construct the pliers at a minimum cost from good material and still produce a plier that is efficient and substantial.

It will be noted that by tightening the bolts 7 and 8, the side plates 6 may be closed in with more or less tension, whereby the working parts are held closely and accurately and there is no looseness either in the original 95 construction or from wear, which is often an objectionable feature in pliers of this class.

What I claim as new and desire to secure by Letters Patent is:

The combination in a compound cutting 100 pliers of a pair of jaw levers having transversely arranged jaws at their ends, a pair of hand levers joined to the jaw levers respectively and connected for simultaneous action, side plates between which the jaw levers and 105 the connecting ends of the hand levers are

located and in which the said levers are severally pivoted with the jaw levers spaced at the pivots to afford a passage and the side plates having openings 9 arranged to afford a 5 passage for the introduction of a wire between the jaw levers and out through the jaws, substantially as set forth.

In witness whereof, I have affixed my signature, in presence of two witnesses, this 6th day of November 1906.

HENRY F. KELLEMEN.
